GEORGE WALWORTH, OF PEEKSKILL, NEW YORK.

Letters Patent No. 88,425, dated March 30, 1869.

IMPROVEMENT IN FLASK FOR MOULDING KETTLES.

The Schedule referred to in these Letters Patent and making part of the same.

To all whom it may concern:

Be it known that I, GEORGE WALWORTH, of Peekskill, in the county of Westchester, and State of New York, have invented a new and useful Improvement in Foundry-Flasks for Sugar-Kettles; and I do hereby declare that the following is a full, clear, and exact description thereof, which will enable those skilled in the art to make and use the same, reference being had to the accompanying drawings, forming part of this specification.

This invention relates to a new and useful improvement in flasks for making certain kinds of castings, but which has more particular reference to the moulding and casting of sugar-kettles; and

The invention consists in so forming the flask that the kettles may be cast right side up, (or as they stand when in use,) instead of bottom side up, as they have hitherto been made, by which improvement they are made with much less labor and risk, and whereby much more perfect castings, or kettles are obtained.

In the accompanying plate of drawings—

Figure 1 represents a vertical section of a flask constructed according to my invention.

Figure 2 is a top view of the flask.

Similar letters of reference indicate corresponding parts.

A is the flask, which is made in two parts, "nowel" and "cope," as such flasks usually are.

A' is the nowel.

B is the cope.

The line of separation is seen at C C, where the two parts are kept in place by steady-pins, or dowels, as seen in the drawings; and when the casting is made, the two parts are clamped together in the usual manner.

D is the bottom board, which is secured to the nowel by clamps, as seen in the drawing.

The flask is made round, or circular, to correspond with the shape of the kettle, and enough larger in diameter and depth to allow a suitable quantity of sand to be rammed around the pattern.

As these kettles have heretofore been made, the mould has been formed in large, square flasks, constructed so as to render the casting of the kettle, bottom side up, unavoidable.

This method of forming the mould and casting the

kettle involved a large amount of labor in ramming so much unnecessary sand, and in handling the flask, the weight of which greatly increased the risk in making the mould.

But the additional labor and risk is not the principal objection to the old method of moulding these kettles.

In pouring the melted metal into a mould, it is well understood by founders, that all the impurities contained in the melted metal, ascend to the top of the casting, as the liquid metal ascends in the mould.

Consequently, in casting the kettle bottom side up, the bottom of the kettle, which should be the soundest and most perfect part, is in fact the most defective.

It is for this reason that cannon, or heavy ordnance, is always cast in pits, in an upright position, breech down, so as to insure solid iron, or metal, where solidity and strength are most needed.

A solid bottom in a sugar-kettle, (which is constantly being exposed to the extremes of heat and cold,) is quite as important.

Where the kettle is cast with the bottom up, it frequently leaks at first, or soon becomes useless, from the spongy nature of the metal.

By forming the flask of such shape and proportion, and arranging the parts, or details of it, so that the kettle may be cast with the bottom down, or "right side up," the labor is not only greatly lessened, but the risk of defective bottoms in sugar-kettles is avoided.

The kettle is "gated" on the top rim, and the "sprues" are set in the projections E.

F represents the wrists on the nowel and on the cope, by which they are handled or lifted by the crane.

G represents the cross-pieces in the cope, for sustaining the sand.

I claim as new, and desire to secure by Letters Patent—

1. The flask A, constructed as shown and described, for casting sugar-kettles, substantially as set forth.

2. The combination of the flask B, having the projections E, with the flask A, substantially as and for the purpose described.

GEO. WALWORTH.
